UNITED STATES PATENT OFFICE

134,786

DESIGN FOR AN APRON

Rebecca White Schenck, Madison, Nebr.

Application May 11, 1942, Serial No. 106,857

Term of patent 3½ years

To all whom it may concern:

Be it known that I, Rebecca White Schenck, a citizen of the United States, residing at Madison, county of Madison, and State of Nebraska, have invented a new, original, and ornamental Design for an Apron, of which the following is a specification, reference being had to the accompanying drawing, forming a part thereof.

The figure on the drawing is a plan view of an apron showing my design.

I claim:

The ornamental design for an apron, as shown.

REBECCA WHITE SCHENCK.
